BARBECUE

Charles B. Polhemus, San Jose, Calif.

Application May 12, 1936, Serial No. 79,249

1 Claim. (Cl. 53—5)

It is one object of the invention to provide a barbecue structure in which the grate may be readily adjusted as to the heating medium without material discomfort to the operator; in which a portion of the grate may be used to support a warming plate if it is so desired, with the said plate permanently associated therewith; in which the parts are so formed and assembled as to provide a strong, substantial and durable device that will be economical to manufacture, and highly efficient in its practical application.

In the drawings:

Figure 1 is a perspective illustration of the structure embodying my invention.

Figure 2 is a plan view of the grate on line 2—2 of Figure 1, with parts broken away.

Figure 3 is a perspective illustration of one of the grate hangers.

Figure 4 is a detail section on line 4—4 of Figure 1.

Figure 5 is a section on 5—5 of Figure 1.

Figure 6 is a perspective view of one of the corners of the grate supporting frame.

Figure 7 is a perspective view of a cable connection to the grate.

Figure 8 is a perspective view of the cable connection to the adjusting lever.

Figure 9 is a perspective view of a portion of the adjusting lever showing the joint at which it may be folded.

Where no other means of attachment is shown it may be assumed that the parts are secured together by spot welding.

The frame forming the base and support for the grate structure may be mounted upon any kind of a pit, a brick pit here being indicated in dotted lines at 1.

The frame 2 is rectangular in form and is made of four lengths of angle iron 3 secured at their corners by triangular corner pieces 4.

Upon each end of the oblong rectangular frame 2 is mounted a bracket 5 having vertical portion 6 spaced back from the inner edge of the frame as shown.

At 7 is shown a U bar in cross section and bent into the form of an inverted U with its two ends resting upon the top of the frame 2 and secured in a vertical position to the inner faces of the two brackets 5. Punched outwardly in the end portions of bar 7 are downwardly inclined fingers 8 to form stops for the purpose hereinafter described. A pulley 9 is journaled in one end of bar 7 to project through an opening 10 therein, and a similar pulley 11 is journaled in a bracket 12 in the other end of the bar as shown.

The grate 13 is formed of two pieces of U bar, each piece having its end portions turned at right angles thereto to form one-half of the end portions of the grate, the flanges of the bar being turned outwardly. The opposing ends of the bars abut each other and are secured by a plate 14 which is formed as at 15 to seat in the said bars along its lower edge.

Extending upwardly from each end plate 14 is a hanger portion 16 provided with a hook as 17, and on the outer side of each portion 16 is mounted a strap as 18 having an outwardly turned lip as 19 to form a stop engageable with the frame 2 to limit the downward movement of the grate.

Mounted upon one corner of the frame 2 is an upstanding bracket 20 in which is pivotally mounted a lever 21. The lever is formed of two parts that are pivotally connected at 22. The outer part 23 is provided with a handle 24 and has a finger 25 turned on its pivoted end to engage a notch 26 on the adjacent end of the other portion whereby the part 23 may be turned back when not in use and yet will be held rigidly in alignment with the first part when fully extended and a downward pressure is applied thereto. An intermediate portion of the lever is bent at an angle thereto as at 27 to engage fingers 8 as desired. A cable 28 is secured to an eye 29 on lever 21, one portion passing over the two pulleys to engage the hook 17 on one hanger 16, and the other passing over one pulley to engage the hook 17 on the other hanger 16. The cable fastenings are shown at 30.

The grate 13 includes the spaced rods 31 upon which the food is placed, and each end of each rod is passed through a hole 32 in the side bar and then upset as indicated at 33, thereby allowing the rod to expand and contract lengthwise and preventing its buckling in the center under wide changes of temperature.

At 34 is shown a plate hingedly mounted as at 35 on one end of the grate and in a position to rest upon the adjacent rods 31 when it is desired to use the plate for cooking purposes or for keeping food warm. When its use is not desired it may be swung into a substantially vertical position out of the way, leaving all of the rods 31 available for barbecue purposes.

The parts 19 slide in the guide formed by the flanges of bar 7 and effectually maintain the grate in a horizontal position and prevent swinging of the same when in use.

It is to be understood, of course, that while I have herein shown and described but one specific embodiment of the invention, changes in form,

construction, and method of assembly and operation may be made within the scope of the appended claim.

I claim:

- 5 A barbecue structure comprising, in combination, an oblong supporting frame having an up-standing bracket mounted on its opposite ends and lying in its median vertical plane to overlie the frame center, a vertically adjustable grate 10 operative to move through the frame and between the bracket end portions in parallel relation with

the plane of the frame, guide means inserted between the grate and bracket end portions, a lever fulcrumed on one end of the frame, sheaves journaled on opposite ends of the bracket, cable means leading from the lever over the sheaves to opposite ends of the grate, and stop means associated with the bracket to engage the lever and thereby support the grate in a desired position relative to the frame.

CHARLES B. POLHEMUS. 10
